UNITED STATES PATENT OFFICE.

CHARLES F. MECHLER, OF CHICAGO, ILLINOIS.

COMPOSING-STICK.

1,102,778.

Specification of Letters Patent.

Patented July 7, 1914.

Application filed May 1, 1914. Serial No. 835,588.

To all whom it may concern:

Be it known that I, CHARLES F. MECHLER, a citizen of the United States, residing at Chicago, in the county of Cook and State 5 of Illinois, have invented certain new and useful Improvements in Composing-Sticks, of which the following is a specification.

This invention relates to composing sticks such as are used by printers for setting type, 10 and the object of the invention is to provide a stick in which the movable knee member may be readily shifted to different positions and yet may be securely locked in place in such a manner as to entirely eliminate the 15 possibility of the knee slipping or springing out of alinement.

Composing sticks have heretofore been produced in which the movable knee member was locked in place by interengaging 20 notches or teeth on the knee member and the body portion, and these teeth have been of various shapes, square, rounded and V-shaped, but in none of the prior sticks, so far as I am aware, could the knee member 25 be positively held from accidental slight displacement under some conditions.

I accomplish my object by providing interlocking teeth of novel and peculiar shape on opposite sides of the knee member and 30 the body portion respectively, said teeth having one edge straight and parallel with the end wall of the body portion, or the flange of the knee member, and the other edge of the teeth being inclined toward said 35 straight edge. The teeth on the knee member, of course, are complementary in shape to those on the body portion. By providing interlocking teeth of this character, the co-operating straight edges of the teeth act to 40 prevent any movement of either edge of the knee member longitudinally of the body portion, even though the knee member is not rigidly clamped to the body portion on account of looseness of the clamping parts or 45 for other reasons.

In the accompanying drawings, Figure 1 is a top plan view of a composing stick embodying the features of my invention. Fig. 2 is a front edge view of the stick. Fig. 3 50 is a section taken in the plane of line 3—3 of Fig. 1. Fig. 4 is the rear side elevation of the movable knee member detached from the body of the stick, and Fig. 5 is a fragmentary underside elevation of the forward portion of the stick and the knee member.

In the preferred form illustrated in the

drawings, my composing stick comprises a bottom or base plate 6, which may be of generally rectangular shape, said plate having rigidly fixed thereto an end wall 7 and 60 a rear wall 8. If desired, the base plate 6 and the rear wall 8 may be formed of an integral piece of sheet metal. Rigidly secured to the forward or inner side of the rear wall 8 is a strip 9 having a series of teeth 10 formed in its lower edge. The strip 9 and the base plate 6 form a groove 11 adapted to receive a part on the movable knee member to be presently described.

Secured to the underside of the base plate 70 6, adjacent to its forward edge is a strip 12 having a series of teeth 13 in its forward edge, said teeth being positioned slightly rearwardly of the forward edge of the plate 6. Preferably the strip 12 is beveled toward 75 the rear so that when the composing stick is laid upon a flat surface, as illustrated in Fig. 3, only the forward portion of the strip 12 and the rear portion of the base 6 will contact with the surface. This construction renders the stick perfectly stable 80 when resting on a flat surface, and obviates the liability of the stick to tilt forwardly in case pressure should be placed upon the forward edge thereof.

The movable knee member 14 comprises a transverse flange 15 disposed parallel to the end wall 7, and a flange 16 lying alongside of the rear wall 8, the latter flange normally contacting the strip 9. A spring clip 17 90 pivoted at 18 to the flange 16 is adapted to embrace said flange and the rear wall 8 to secure the knee member in place, said clip having a thumb-piece 19 for operating it. At the lower rear side of the flange 16 of the 95 knee member is a rib 20 having at its upper side a suitable number of teeth 21, said rib and teeth lying within the groove 11 in the rear wall and co-operating with the locking teeth 10. At the forward edge of the knee 100 member 14 is a downwardly and rearwardly turned flange 22 having teeth 23 to interlock with the teeth 13 on the strip 12. Particular importance is ascribed to the shape of these locking teeth. As will be seen from Figs. 105 1 and 2, the edges of the teeth 10 and 13 facing the end wall 7 are straight and parallel to said end wall, or in other words, lie in planes extending at right angles to the stick. The opposing edges of the teeth are inclined 110 toward said straight edges. The teeth 21 and 23 of the knee member are, of course, of

complementary shape to interlock with the teeth 10 and 13. The interlocking teeth are depended upon exclusively for holding the knee member against displacement, the 5 spring clip 17 serving only to hold the knee member in place with the teeth in engagement. Owing to the fact that interlocking teeth are provided both at the rear side and the forward edge of the knee member, and 10 due further to the fact that the abutting edges of the locking teeth on the body and the knee member, respectively, are straight and parallel with the end wall 7, it will be impossible for the knee member to be sprung 15 out of alignment with said end wall even if the knee member is given a slight amount of play due to looseness of the clamp 17 or from other causes. Absolute and indestructible alignment is one of the essential features of 20 a successful composing stick of this character, and I believe myself to be the first to provide a composing stick having a movable knee member in which the possibility of disalignment or displacement is entirely eliminated.

A scale 24 is provided on the upper face of the base plate 6 adjacent to its forward edge to assist the typesetter in properly positioning the knee member 14. If desired, a 30 scale 25 extending transversely of the base plate 6 may also be provided. Preferably the forward lower edges of the teeth 13 on the strip 12 are rounded and smoothed in order to avoid annoyance or injury to the 35 hand of the operator holding the stick.

When it is desired to adjust the width of the column of type being set, the spring clip 17 is swung upwardly out of engagement with the rear wall 8, the knee member is 40 moved forwardly to disengage the interlocking teeth and then longitudinally of the body of the stick, and finally rearwardly into engagement with the teeth in its new

position, and the clip 17 is then swung downwardly to secure the knee member in 45 place. The inclined edges on the teeth facilitate the positioning of the knee member because said inclined edges cause the interengaging teeth to slide along each other into position with the straight edges in contact.

As will be understood, my invention provides a composing stick in which the movable knee member is easily and quickly adjustable to any desired position, and at the 55 same time is capable of being positively locked so as to entirely obviate any danger of slippage or disalignment.

I claim as my invention:

In a composing stick, in combination, a 60 body portion comprising a base plate having secured thereon an end wall and a back wall, the latter having a row of locking teeth at its forward side, said base plate having a 65 row of locking teeth adjacent to its forward edge, the sides of all of said teeth which face said end wall being straight and parallel to said end wall and the opposite sides of said teeth being inclined; and a knee member movably mounted on said body portion and 70 having locking teeth at its forward and rear edges complementary in shape to the first mentioned locking teeth and adapted to co-operate therewith; and a clip mounted on the knee member and adapted to engage said 75 body portion to hold the knee member in position with the straight walls of said locking teeth in engagement with each other at the forward and rear side of the stick.

In testimony whereof I affix my signature 80 in presence of two witnesses.

CHARLES F. MECHLER.
